ELLSWORTH E. CLARK AND ADOLPH ROSENBERG, OF BUFFALO, NEW YORK, ASSIGNEES
TO CLIMAX LOCK AND VENTILATOR CO., OF BUFFALO, NEW YORK.

ANTIRATTLER FOR WINDOWS.

965,988.

Specification of Letters Patent. Patented Aug. 2, 1910.

Application filed May 26, 1909. Serial No. 498,478.

To all whom it may concern:

Be it known that we, ELLSWORTH E. CLARK and ADOLPH ROSENBERG, citizens of the United States, both residing at Buffalo, 5 in the county of Erie and State of New York, have invented certain new and useful Improvements in Antirattlers for Windows, of which the following is a specification.

This invention relates to window attachments and refers particularly to a device to be applied to the windows for the purpose of preventing the rattling of the same.

The invention has for an object the provision of an improved device which is applicable to window sashes and which is adapted to prevent the rattling of the same should the sashes be loosely mounted within the supporting casing and to provide such a device which may be applied readily to any 20 form of sash construction.

The invention further contemplates the provision of a device of this character which is formed of a portion of metal bent and stamped or cast into the required shape and 25 which thereby produces an efficient, durable and compact device.

For a full understanding of the invention reference is to be had to the following description and accompanying drawings, in 30 which:—

Figure 1 is a fragmentary perspective view of a window frame and sash mounted in the same having the improved device applied thereto. Fig. 2 is a vertical horizontal section through the sash and casing disclosing the device as applied thereto, and Fig. 3 is a detailed perspective view of the improved device.

Corresponding and like parts are referred 40 to in the following description and indicated in all the views of the drawing by the same reference characters.

Referring to the drawing the numeral 10 designates an arcuate strip of metal which 45 is provided upon its inner extremity with a curved lip 11 bent at a slight angle outwardly from the body portion 10 and is provided at its opposite extremity with a turned over portion 12 for forming a grip for the 50 hand of the operator in manipulating the anti-rattler. The strip 10 is laterally curved

to form a cam face 13 for the purpose of wedging the frame of the sash 14 between the dividing strip 15 of the casing 16 and the retaining strip 17.

The means employed for supporting the arcuate strip 10 upon the sash 14 comprises a lug 18 which is inwardly extended from the edge of the same and which is offset inwardly in order to engage against the face 60 of the sash 14 and to permit of the extending of the outer end of the strip 10 away from the side of the frame 14 owing to the cam construction of the same.

The overturned portion 12 is curved inwardly to lie in a plane with the inner end of the strip 10 and in alinement with the curved lip 11. The device is supported upon the sash 14 by means of a suitable screw or pin 19 or the like which is engaged 70 through an aperture formed in the lug 18 and secured in the frame of the sash 14 to permit of the swinging of the lug 18 about the same.

In the drawing the device is disclosed as 75 being applied to the side of the sash 14 and having the curved lip 11 engaged against the inner face of the retaining strip 17 so that when it is necessary to jamb the sash 14 within the casing 16 to correct the rattling of the same the operator grasps the outer end of the arcuate strip 10 and forces the same inwardly toward the casing 16 whereby the cam face 13 is forced inwardly and caused to impinge against the inner face 80 of the retaining strip 17 thereby preventing 85 the rattling of the sash 14.

It is readily seen that this device may be applied to any portion of the sash which will admit of the jambing of the same 90 against a fixed member, or it may be applied to any device wherein a cam retaining member is adaptable.

The device, it is observed is stamped from sheet metal or could be cast when the lug 18 95 and the turned over portion 12 are formed and the lip 11 is curved outwardly.

Having thus described the invention what is claimed as new is:—

An anti-rattler for windows including an 100 arcuate strip curved longitudinally to form a cam, an offset lug formed at one edge of

said strip for engagement against the window to pivotally support said strip, a lip formed upon the inner end of said strip to engage between the window and the frame 5 therefor, and a turned over portion on the outer end of said strip to support the cam and to serve as a handle for said strip.

In testimony whereof we affix our signatures in presence of two witnesses.

ELLSWORTH E. CLARK. [L.S.]
ADOLPH ROSENBERG. [L.S.]
